UNITED STATES PATENT OFFICE.

GEORGE D. WANNER, OF DAYTON, OHIO.

KITE.

1,321,957.

Specification of Letters Patent. Patented Nov. 18, 1919.

Application filed June 28, 1919. Serial No. 307,364.

To all whom it may concern:

Be it known that I, GEORGE D. WANNER, a citizen of the United States, residing at Dayton, in the county of Montgomery and State of Ohio, have invented certain new and useful Improvements in Kites, of which the following is a specification, reference being had therein to the accompanying drawing.

10 This invention relates to improvements in kites and has for its object to provide a kite of relatively simple and substantial construction which can be produced at relatively low cost and which will be of a construction convenient for boxing or to be put up in compact packages or bundles suitable for quantity shipping and stocking.

To this end my invention consists of an improved K. D. kite, that is to say, a kite 20 adapted to be disassembled, or partially so, for packing and shipping, and which may be readily and effectually assembled by any boy without possibility of failure to fly properly.

25 A particular object of my invention is to provide a kite which may be made and sold cheaply, but which will nevertheless be substantial and in all respects admirably adapted for its purposes.

30 These features of relatively low cost and durability are of first importance in this art in view of the fact that kites, generally speaking, because of their delicate construction and the average condition under which 35 they are flown, are short lived. A few cents reduction in the price at which they may be purchased therefore amounts to a substantial difference when measured by the limited finances or trading capital of the 40 average boy.

In the accompanying drawings:

Figure 1 is a rear elevation of a kite embodying my invention;

Fig. 2 is a detail view showing the kite 45 disassembled and wrapped ready for box or bundle packing;

Fig. 3 is a top edge view of the kite;

Fig. 4 is a detail view showing the manner 50 of detachably connecting the cross stick to the upright stick;

Fig. 5 is a detail view showing the manner of detachably connecting the bow cord and the bounding cord to the ends of the cross stick;

55 Fig. 6 is a detail view showing the manner of adjustably connecting the bounding

cord to the lower end of the upright stick; and

Fig. 7 is a detail view showing the method of adjustably connecting the bridle loop 60 to the bridle string.

As shown in the drawings, my improved kite consists of the usual features of an upright stick 1, a cross or bow stick 2, a bounding cord 3 and a bow cord 4. These features constitute the frame structure of the kite, and, generally speaking, are substantially like the corresponding features of the usual well known construction of kites.

The cross stick is connected to the upright stick, the bounding cord 3 extends over and between the ends of the oppositely disposed sticks, and a cover 5 is secured to the kite frame thus defined in the usual manner except with regard to certain improved features which will now be described in detail.

To provide for convenient disconnecting of the cross stick from the upright stick and the cords 3 and 4, the cords are provided with loops 6 adapted to engage pins 7 secured in the opposite ends of the cross stick, as best shown in Fig. 5. The cross stick is detachably connected to the upright by means of a staple guide 8 having its 85 prongs extending on opposite edges of the cross stick and through the upright, the projecting ends thereof being clenched, as shown at 9.

Thus by disconnecting the loops 6 from 90 one of the pins 7 the cross stick may readily be withdrawn from the guide 8 and the kite will thereby be collapsed, and, by placing the bow stick lengthwise of the upright stick, the kite cover may be wrapped closely 95 about the sticks longitudinally of its length, as shown in Fig. 2.

The opposite ends of the upright stick are provided respectively with a slot 10 and a pin 11. The bounding cord 3 is tied to 100 the pin 11 substantially centrally between the ends of the cross stick, the opposite lengths of the cord being looped over the pins 7 in the ends of the bow stick, as above stated, and tied as at 12, one length 105 of the cord passing fully through the slot 10. The cord being secured to the pin 11, its opposite extensions may be drawn taut and its free ends tied as stated, thus completing the skeleton outline or frame of the 110 kite. The cover 5 may then be secured to the cord by having its edges folded over

the cord and pasted down, as indicated at 12 in Fig. 1.

A bridle 13, as here shown, is secured to the upright stick by upper and lower staples 5 14 and 15, the staples being substantially the same and secured to the upright in the same manner as the staple 8.

The bridle spring loop 16 is adjustably secured thereto, as best shown in Fig. 8, by 10 encircling the string with the loop, then passing one end of the loop through the opposite end thereof and drawing it taut to the bridle in an ordinary slip knot. Thus by opening the knot the loop may be 15 adjusted relative to the bridle as required to suit the conditions of flying. To complete the kite the flying string 17 is secured to the bridle loop in any suitable manner.

It is obvious, of course, that the purposes 20 of the improved construction may be met by making the looped connections of the bounding and bow cords at one end of the cross stick only, the connections at the opposite end being of any suitable character; 25 also that in place of the slot 10 any other suitable means may be provided to connect the bounding cord adjustably to the lower end of the upright stick.

Having thus fully described my inven-

tion, what I claim as new and desire to secure by Letters Patent, is:—

1. In a kite, a frame comprising an upright stick and a cross stick, and a bounding cord secured to one end of said upright, adjustably connected to the opposite end 35 thereof and looped intermediate its connections to the upright stick over pins secured in the ends of the cross stick.

2. In a kite, a frame comprising an upright stick and a cross stick, and a bounding cord fixed to one end of said upright and passing freely through a slot formed in the opposite end thereof being looped intermediate its connections to the upright stick over pins secured in the opposite ends of 45 the cross stick.

3. In a kite, a frame comprising an upright stick and a cross stick detachably secured thereto by a staple secured in said upright, a bounding cord secured to the frame 50 and looped over pins secured in the opposite ends of the cross stick, whereby by disconnecting said loop from said end the cross stick may be detached from the upright stick. 55

In testimony whereof I affix my signature.

GEORGE D. WANNER.
